CLOTHES SPRINKLER

Wilmer August Otto Schultz, Madawaska,
Ontario, Canada

Application April 1, 1932, Serial No. 602,576

5 Claims. (Cl. 299—121)

This present invention relates to certain new and useful improvements in a clothes sprinkler.

The primary object of the invention resides in the provision of a clothes sprinkler of generally improved and simplified construction and increased efficiency.

The invention has for another object the provision of a clothes sprinkler of the character stated which may be readily attached to or removed from a faucet or the like and which is of such construction that it will occupy the minimum space when not in use.

The invention has for a further object the provision of a clothes sprinkler of the character stated which is of such construction that it is always under the control of the operator to regulate the discharge of water or any other preferred liquid in a fine spray for sprinkling or dampening clothing and other articles previous to ironing of the same.

The invention has for a still further object the provision of a clothes sprinkler of the character stated which is of extremely simple and inexpensive construction and composed of the minimum number of parts as well as of special and improved design and furthermore is of such a type and character that it may be readily manufactured at small cost and retailed at a popular price with good profit, thus providing a commercially attractive proposition.

To the accomplishment of these and related objects as shall become apparent as the description proceeds, my invention resides in the construction, combination and arrangement of parts as shall be hereinafter more fully described, illustrated in the accompanying drawing and pointed out in the claims hereunto appended.

The invention will be best understood and can be more clearly described when reference is had to the drawing forming a part of the disclosure, wherein like characters indicate like parts throughout the several views.

In the drawing:—

Figure 1 is an elevation of the improved clothes sprinkler, showing the same attached to a faucet for obtaining water under pressure; and

Figure 2 is an enlarged detail longitudinal section through the improved clothes sprinkler.

Referring more in detail to the drawing, it is to be noted that the clothes sprinkler includes a liquid reservoir 6 having a screening saucer 7 around its lower portion and spaced therefrom by the downwardly and outwardly diverging attaching strap 8 or other appropriate means extended from the bottom 9 of the liquid reservoir 6 to the

bottom of the screening saucer 7, on the inner face of the latter and at the connection of the flanged upstanding edge or side 10 thereof with the bottom or main portion thereof. This screening saucer is formed of a fine wire mesh or other appropriate material. The liquid reservoir 6 has a plurality of arcuate slots 11 in the wall thereof, slightly below the centre of the reservoir 6 and also slightly below the top of the flanged edge or side 10 of the screening saucer 7. These slots 11 serve as discharge slots for the liquid reservoir 6 and the upper walls 12 of the narrow arcuate slots 11 are flanged or pressed outwardly so that the liquid may be discharged from the liquid reservoir 6 into the screening saucer 7 and at the same time directed downwardly against the inner face of the inclined edge or side 10 of said screening saucer 7 so as to assure breaking up of the liquid into a fine spray as it strikes the screening saucer 7 and passes through the small openings 10 thereof. The liquid reservoir 6 has a separate neck 13 threaded in the centre of its upper end and provided with an outwardly directed annular flange 14 at the upper edge of the neck 13. This neck 13 has mounted thereon the coupling member 15 with the inturned annular flange 16 at the lower end thereof engaged on the neck 13 below the out-turned annular flange 14 at the upper edge of the latter. The coupling member 15 is in turn threaded on the enlarged lower end 17 of the 15 hollow elongated handle or hand-grip 19. An appropriate straining disc 20 is positioned between the flange upper end of the neck 13 and the enlarged exteriorly threaded lower end 17 of the reduced 20 downturned end 18 of the hollow handle or hand-grip 19, and one or more packing rings 21 are 25 also employed beneath the neck 13 and the said lower extremity 17 of the downturned handle or hand-grip end 18 to form a water-tight connection between these parts.

A valve seat 22 is provided in the elongated hollow handle or hand-grip 19 at the connection of the main portion thereof with its downturned end 18 and a control valve 23 of the beveled disc 45 or frusto-conical type is normally seated on the valve seat 22 to close communication between the main portion of the elongated hollow handle or hand-grip 19 and the downturned end thereof. This control valve 23 is carried on the inner end 50 of a valve stem 24 slidable through a valve stem opening 25 in the downturned end 18 of the elongated hollow handle or hand-grip 19, an arcuate head 26 being provided on the outer extremity of the valve stem 24. A cap 27 is mounted on the 55

valve stem 24 and threaded on a reduced extension 28 projecting laterally from the downturned end 18 of the elongated hollow handle or hand-grip 19, said cap 27 serving to maintain a suitable packing 29 in a recess 30 provided therefor in the outer extremity of the extension 28.

The elongated hollow handle or hand-grip 19 has a reduced exteriorly threaded extension 31 at its opposite end for supporting one extremity 32 of a flexible hose section 33 or the like, removably mounted on said exteriorly threaded reduced extension 31. This flexible hose section 33 has its opposite extremity 34 arranged for removable mounting on a conventional water faucet 35 or the like and adapted to be held firmly on the latter by an elastic band 36 projecting at an angle from said flexible hose section extremity 34 for engagement over the body of the faucet 35. The elastic band 36 has a lateral loop extension 37 at its central portion also designed for engagement over the faucet 35 at a right angle to the main portion of the elastic band 36, the lateral loop 37 being connected at its centre with the flexible hose extremity 34 by a flexible connecting strap 38. Thus, the flexible hose section 33 may be readily clamped upon and will be firmly held on the faucet 35.

As the construction of the device has thus been described in detail, brief reference is now had to its use and modus operandi: When the clothes sprinkler is to be used, it is firmly attached to a water faucet 35 or the like by means of the elastic band 36 and the central lateral loop 37 and flexible strap 38. Then the device is held by the elongated hollow handle or hand-grip 19 and the thumb or a finger employed against the arcuate head 26 at the outer end of the valve stem 24 to force the valve 23 away from the valve seat 22 and thus permit water or the like to pass the valve 23 and valve seat 22 and continue through the straining disc 20 to the liquid reservoir 6, the liquid pressure being controlled by the faucet 35. Thus, the liquid under pressure will be forced from the liquid reservoir 6 outwardly by way of the slots 11 with force into the screening saucer 7 and through the small openings of the latter in the form of a fine spray onto the clothing or other articles to be sprinkled. During use of the sprinkler, the faucet 35 may be left open and the liquid pressure against the valve 23 will then serve to normally maintain this valve in its closed or seated position, the valve 23 being opened as required by pressure against the arcuate head 26 at the outer end of the valve stem 24. It is also apparent that the liquid employed will be thoroughly strained and screened by the straining disc 20 and the screening saucer 7, before being released in the form of a spray onto the clothing or other articles being sprinkled. All of the parts of the device may be readily connected together or taken apart, as desired and when not in use, the entire device will occupy only the minimum amount of space. Furthermore any of the parts of the device may be readily repaired or replaced at small cost and without requiring the services of a special or trained workman for disconnecting or reassembling the parts of the device.

From the foregoing description taken in connection with the accompanying drawing, it will be manifest that a clothes sprinkler is provided that will fulfill all the necessary requirements of such a device but as many changes could be made in the above description and many apparently widely different embodiments of my invention

may be constructed within the scope of the appended claims without departing from the spirit or scope thereof, it is intended that all matters contained in the said accompanying specification and drawing, shall be interpreted as illustrative and not in a limitative or restrictive sense.

Having thus described my invention, what I claim as new and desire to secure by Letters Patent is:—

1. A clothes sprinkler adapted for connection to a source of liquid under pressure including a liquid reservoir having narrow outwardly and downwardly discharging slots provided in the side walls thereof; a screening saucer underlying and surrounding a portion of said liquid reservoir and receiving the liquid from the latter through said slots; an elongated hollow handle connecting with and supporting said liquid reservoir to supply a liquid thereto under pressure; straining means for said liquid carried by said handle; and means operable in said handle for controlling passage of the liquid through the same.

2. A clothes sprinkler including a hollow handle having a portion thereof serving as a hand-grip; said handle having reduced end extensions; a liquid reservoir; means for detachably mounting said liquid reservoir on one of the end extensions of said handle; a liquid straining member removably held between said liquid reservoir and the handle extension on which said liquid reservoir is mounted; a screening saucer surrounding and spaced from a portion of said liquid reservoir; said liquid reservoir having flanged arcuate narrow openings in the sides thereof for discharging a liquid from said liquid reservoir against the sides of said screening saucer; and a control valve for said handle normally maintained in closed or seated position therein by the liquid; and means on said control valve whereby the latter may be unseated from outside of said handle.

3. A clothes sprinkler including a liquid reservoir having arcuate flanged discharge slots in the sides of its lower portion; a screening saucer mounted on and spaced around said lower portion of the liquid reservoir; a hollow handle serving as a hand-grip and having a turned reduced end extension; means for removably mounting said liquid reservoir on said end of the handle; a liquid straining member supported in the last mentioned means and a thumb operable control valve for said handle to control passage of a liquid through said handle and to said liquid reservoir; said control valve being adapted to be opened from outside of said handle by pressure of the thumb of the operator holding said handle.

4. A clothes sprinkler including a hollow handle adapted for connection to a source of liquid under pressure, a portion of said handle serving as a handgrip; a reduced turned extension on the other end of said handle; a thumb operated reciprocable valve axially aligned with said handle and projecting through said turned end normally held closed by the pressure of liquid within said handle; a liquid reservoir detachably mounted on said turned end; said reservoir having a closed bottom and a plurality of circumferentially spaced flanged arcuate outwardly and downwardly discharging openings in its side walls and a screen saucer underlying and surrounding the lower end of said reservoir and reaching up to at least as high as said circumferential row of openings suspended beneath said reservoir by a plurality of attaching straps.

5. A clothes sprinkler including a screening

saucer; a liquid reservoir supported in said screening saucer and provided with arcuate discharge slots in the sides thereof for discharging a liquid from said reservoir against the sides of said screening saucer; a hollow handle for said liquid reservoir; a straining member carried in

said handle; means for detachably connecting said liquid reservoir to said handle; a portion of said handle serving as a hand-grip; and a normally seated reciprocable control valve within said handle.

WILMER AUGUST OTTO SCHULTZ. [L.S.]
